UNITED STATES PATENT OFFICE.

MAX SEIDLER, OF FRANKFORT-ON-THE-MAIN, GERMANY, ASSIGNOR TO THE FIRM OF
HARTMANN & BRAUN A.-G., OF FRANKFORT-ON-THE-MAIN, GERMANY.

RECORDING APPARATUS.

1,213,491.

Specification of Letters Patent.

Patented Jan. 9, 1917.

Application filed January 7, 1914. Serial No. 810,749.

To all whom it may concern:

Be it known that I, MAX SEIDLER, electrician, a citizen of the German Empire, and residing at Frankfort-on-the-Main, Province of Hesse-Nassau, in the Kingdom of Prussia, Germany, have invented certain new and useful Improvements in Recording Apparatus, of which the following is a specification.

10 This invention relates to improved means adapted for use in concurrently producing upon the same strip or chart records or diagrams relative to several electric currents, and has for its object to enable such diagrams to be produced by means of a single apparatus in such a manner that, even where partly superimposed or intersecting, they do not become confused and may readily be followed.

20 In the accompanying drawings, Figure 1 illustrates a portion of such a strip or chart produced according to methods hitherto known and shows how confused and difficult to follow the diagrams become. Figs. 2 and 3 are respectively a side elevation and a transverse section illustrating one method of carrying out my present invention; Figs. 4 and 5 being like views illustrating a modified form of the latter. Figs. 6 and 7 are, again, similar views illustrating a further alternative construction, while Figs. 8 and 9 are transverse sections illustrating other modified forms of the invention. Figs. 10 to 14 are detail sectional views. Figs. 15 and 16 are side views of modified forms of the inventive idea. Figs. 17, 18 and 19 show an alternative construction in transverse section and side elevation. Fig. 20 is a perspective view showing the general disposition of the apparatus.

Recording apparatus producing intermittent markings or diagrams are sometimes so constructed as to permit of several magnitudes being registered by means of a single instrument on the same recording strip or chart. The application of this form of apparatus to galvanometers for a number of electric thermometers situated perhaps some distance apart, is an important example. If, under such conditions, several temperatures are approximately the same, curves are formed which lie so close together, or intersect one another to such an extent that they become much confused, and errors in

following them may easily occur. In Fig. 1 at the top is illustrated a portion of a strip on which this has occurred, and it will be readily seen that it is impossible to follow with certainty the paths of the separate curves. For this reason it has already been proposed to render the diagrams or curves more easily distinguishable by the use of different colors. The methods hitherto devised have, however, been very complicated particularly where more than two colors have been employed; the reason being that the color-bearing bodies are on the same side of the recording strip as the marking point. Hence they have required to be inserted between the latter and the paper, and consequently have occupied, when more than two in number, a considerable amount of space, thus causing some difficulty in changing the paper.

According to the present invention, the magnitudes of various circuits may be recorded on the same strip by means of a simple measuring instrument, in such a manner as to be clear and easily readable. The color bearing bodies are arranged on the side of the paper remote from the marking point and automatically change positions in definite order. Electric apparatus for other purposes in which the recording is similarly effected on the reverse side of the paper to the marking point, are well-known. The attempt has moreover already been made in instruments of this kind, to render the records or diagrams distinguishable either by making them inherently different, or by changing the type. (cf. U. S. P. No. 965,754). But by these means, the object of this invention, namely the production of a considerable number of easily distinguishable curves, cannot be so fully attained, not only because they are constructed for a single color only, but because they are incapable of registering curves which intersect each other according to variations in the magnitudes.

According to this invention, a practical instrument for the production of several curves in different colors is obtained by the arrangement of bodies bearing various colors in the form of an endless chain, in such a manner that the changing over of the measuring instrument on to a fresh circuit is automatically accompanied by a forward

2
motion of the series of color-bearing bodies, and a fresh color is brought beneath the marking point.

A simple mode of execution of the idea of the invention is shown. In Figs. 2 and 3 is illustrated the application of my invention to a recorder for 6 circuits comprising a single measuring instrument in which the path of deflection of the marker is curved. The several color-bearing bodies f^1-f^6 , which preferably assumes the form of ribbons or pads, are mounted on a hexagonal barrel which pivots around the axle a , and lie within metal shields b . The latter are provided with curved slots or openings corresponding to the path of deflection of the marker, through which the recording strip r is pressed, by means of the marking point z , against the color-bearing body and is thus marked.

An alternative method of constructing the color changing device for measuring instruments in which the path of deflection of the marker is curved, is illustrated in Figs. 4 and 5. In this case, the color-bearing bodies f^1-f^6 are carried by an endless ribbon c , which traverses the rollers w, w and passes between the support m and the metal shield b . The recording strip runs over this shield b , and is marked in the manner above described. Instead of separate color bearing bodies, the ribbon itself may, where desired, be impregnated with the required colors. If the marker be deflected in a straight line, it is advisable to unite the color-bearing bodies in the form of a roller, as shown in Figs. 6 and 7: the protecting shield for preventing the strip coming into direct contact with a color-bearing body, assuming the form of a tube with straight slots or openings.

In Fig. 8 is illustrated in section a color roller within which rotatable color-bearing bodies are arranged instead of rigidly mounted pads. The advantage of this construction is that as these rollers are rotated, a fresh portion of their surface is presented to the marker and their unusable surface is thus considerably increased. The device may, in fact, be so constructed that the small rollers are automatically rotated by the movement of the main roller, so that unused portions of color surface are continually being presented.

In Fig. 9 is illustrated a modified construction of the multi-color roller adapted for use where the marker z assumes the form of a knife edge whereby the actual marking is effected. The individual color-bearing body is in this instance presented as a fine edge, which can be provided by employing a ribbon held between segments of the metal roller, the outer edge of the ribbon extending slightly above the surface of the latter. The inner edge may in addi-

tion be in communication with a color pad carrying a considerable quantity of liquid color from which the ribbon is continually re-impregnated. The actual coloring body exposed to the recording strip is thus presented in the form of a line, but possesses far more color reserve than a simple thread. The superiority of this device over those hitherto proposed in which the marking is also effected by means of a knife edge and a coloring body in the form of a line which is rapidly exhausted of color will be readily perceived. Furthermore, it is not practicable for technical reasons to employ such a color roller embodying a color reservoir in a position above the recording strip. The form of the color roller may, where desired, be such that it corresponds to the curved path of the marker, when this movement takes place over a cylinder parallel to the axis of the measuring instrument.

The new method of recording according to the invention consists essentially in automatically bringing the color-bearing bodies in succession beneath the marking device and hence requires special designs of the color-bearing bodies: Owing to the comparatively strong pressure which is exerted on the marker d fixed on the pointer z and the yielding character of the coloring pads hitherto used these latter cannot be employed in connection with the present invention.

Fig. 10 illustrates an improved coloring pad wherein b is a cover of an absorbent material, a a porous inlet and c a solid support of any suitable material, for example, metal. Hence only the thin cover is exposed to the pressure of the marker and the cover, owing to its absorbing tendency, is continuously re-impregnated. It will be clearly seen that this arrangement permits to obtain very distinct marks on the reverse side of the paper instead of large blots.

The particular design of the coloring body is important especially when the marker d is knife-edged in the known manner. In Fig. 15 the color-bearing body b assumes, like the pointer d , the form of a knife edge so that when the latter is pressed down a distinct dot will be obtained at the point of contact.

Fig. 11 shows in detail the color-bearing body which consists of the absorbent cover b , the porous color pad a , which by way of example may consist of felt, and the solid inlet c . It will be readily seen that the knife-edged marker d , when pressed down, is prevented from penetrating into the color bearing body. Fig. 12 shows similar form of the same adapted especially for use in connection with the construction illustrated in Fig. 14. The color-bearing body shown in Fig. 13 is distinguished by the former ones in that the cover and the coloring body

are made out of the same piece of fabric or other suitable material which is folded once or several times except at the point exposed to contact with the marker. The pad-like coloring body is easily to be manufactured and will be sufficient in most cases especially in cases where a plurality of color-bearing bodies is successively operated. Such a contrivance is shown in Fig. 15 and it is obvious that, the part of the color-bearing body *b* exposed to the marker *d* being confined to a very fine edge, the greater part of the absorbent cover can be used as and replace the color pad. This arrangement offers the further advantage that the color-bearing bodies when exhausted, can easily be renewed.

Fig. 16 illustrates a further modification of the color-bearing body wherein a particular ink pad *a* is used. As compared with the above described this construction is distinguished by the ink pad being arranged outside the coloring body instead of within. This arrangement has the same technical effect as that disclosed in Fig. 15 but offers besides the advantage of permitting the ink pad *a* to be easily clamped between the cheeks *p*₁ *p*₂ with fixed distance *z*.

Fig. 17 shows an alternative form which the invention may assume and the importance of which will be readily understood when looking at Figs. 18 and 19. To obtain a plurality of coloring bodies it has been proposed already to use a series of silk threads. It will be understood, however, that the capacity for the coloring liquid of the simple silk thread is confined to a very small amount. According to my invention the thread *b* is extended above the ink pad *a* in such a manner that practically it forms a cover for the latter. The ink pad *a*, which consists preferably of a woolen thread or wick, is embedded in grooves provided in the solid cylinder *c* in such a manner that the remaining edges form an abutment between *b* and *a* for the marker *d*. The manner in which the coloring body is automatically brought into position is exceedingly important for the reliable working of the new multi-color recorder.

In Fig. 20 is illustrated the relative position of the marker *z*, presser frame *d*, the coloring body *f*, and the switch *u*, to the contact pieces 1-6 of which the circuits to be recorded are connected. By means of the clockwork *e* or an intermittently acting electro-magnet which moves the recording strip, the point of the marker *z* is thrust by means of the presser frame *d* against the recording strip. The ratchet hook *h* catches in successive pins *s* upon each movement, and its return motion causes the prism or roller bearing the separate color bodies to advance the space of one color, the brush of

the switch *u* being thereby advanced to the next contact piece. The whole preparation for registration is thus completed, and this registration duly follows as soon as the electric turning device has stopped. In this 70 form of construction particular importance attaches to the working of the switch *u*, which is connected either directly, as shown, or by means of gear wheels to the roller or barrel or its axle, in such manner that the 75 recording strip must necessarily be marked with the correct color corresponding to any position of the switch. This arrangement of the switch presents material advantages over and is quite different from that employed in the known single color instruments, in which the switch is either directly connected to the clockwork, or is constructed independently of the recording apparatus, although electro-magnetically operated by 80 the latter. Where desired, the movement of the color roller may, again, be such as to only bring the colors successively beneath the marker, the roller being turned back under the influence of a spring or the like 85 after the last color has been used into its first position.

Now what I claim is:—

1. In recording apparatus, means to produce, by means of a single marking device impinging upon a common strip arranged between the said marking device and the color bearing body, records or diagrams relating to several electric currents, and wherein a number of differently colored 100 pads or the like are in succession automatically brought beneath the marking device.

2. In an apparatus for recording characteristics of a plurality of electric circuits, a single marking device whose actuation is 105 controllable by each of said circuits, a series of movable color-bearing bodies, one color for each circuit, means for bringing a particular one of the color-bearing bodies to position adjacent the marker when the 110 marker is actuated by the circuit corresponding to that color, and a record sheet passing between the marker and the color-bearing bodies.

3. In an apparatus for recording characteristics of a plurality of electric circuits, a single marking device whose actuation is controllable by each of said circuits, a series of movable color-bearing bodies, one color for each circuit, means for causing the actuation of said marking device by the several electric circuits in succession and for moving the color-bearing bodies in a corresponding succession so as to bring a particular one of the color-bearing bodies to 125 position adjacent the marker when the marker is actuated by the circuit corresponding to that color, and a record sheet passing between the marker and the color-bearing bodies.

4. In an apparatus for recording characteristics of a plurality of electric circuits, a single marking device whose actuation is controllable by each of said circuits, a series 5 of movable color-bearing bodies, one color for each circuit, means for causing the actuation of said marking device by the several electric circuits in succession and for moving the color-bearing bodies in a corresponding succession so as to bring a particular one of the color-bearing bodies to position adjacent the marker when the marker is actuated by the circuit corresponding to that color, and a record sheet moving intermittently between the marker and the color-bearing bodies, in consonance with the movements of the latter.
5. In an apparatus for recording characteristics of a plurality of electric circuits, a single marking device whose actuation is controllable by each of said circuits, a series 10 of movable color-bearing bodies, one color for each circuit, means for bringing a particular one of the color-bearing bodies to position adjacent the marker when the marker is actuated by the circuit corresponding to that color, a record sheet passing between the marker and the color-bearing bodies, and means for causing a relative movement between the marking device and the color-bearing body which is in position adjacent the same so as to cause an imprint to be made upon the record sheet from said color-bearing body.
- 35 6. In an apparatus for recording characteristics of a plurality of electric circuits, a single marking device whose indicating position is controllable by each of said circuits, a series of movable color-bearing 40 bodies, one color for each circuit, means for bringing the color-bearing bodies successively to position adjacent the marker when the marker is actuated by the circuit corresponding to that color, means for successively bringing the several color-bearing bodies to position adjacent the marker and causing a relative movement between the marker and each color-bearing body as the latter is brought into position adjacent thereto.
- 45 7. In an apparatus for recording characteristics of a plurality of electric circuits, a single marking device whose indicating position is controllable by each of said circuits, a series of movable color-bearing bodies, one color for each circuit, means for bringing the color-bearing bodies successively to position adjacent the marker when the marker is actuated by the circuit corresponding to that color, means for successively bringing the several color-bearing bodies to position adjacent the marker and causing a relative movement between the marker and each color-bearing body as the latter is brought into position adjacent thereto.
- 50 8. In a device of the kind described, a rotating cylindrical member, a plurality of color-bearing bodies carried thereby and presented around the periphery thereof, a marker, means for causing partial step-by-step rotations of the cylindrical member to bring the successive color-bearing bodies into position adjacent the marker and for causing relative movement between said marker and each color-bearing body as the latter is brought to position adjacent the marker, and a switch controlled by the last-named means for connecting the marker successively with the several circuits of a plurality of circuits corresponding in number to the number of color-bearing bodies.
9. In a device of the kind described, a cylindrical member, a series of color-bearing bodies disposed in regular arrangement around the periphery of the cylindrical member, each extending lengthwise thereof, a marker having a path of movement lengthwise of the cylindrical member, means for giving the cylindrical member a partial step-by-step rotation so as to bring the color-bearing bodies successively into position adjacent the marker, and means for causing relative movement between the marker and the color-bearing bodies as the latter are successively brought into position adjacent the marker.

In testimony whereof I have affixed my signature in presence of two witnesses.

MAX SEIDLER.
